UNITED STATES PATENT OFFICE.

FRED RICE, OF MINNEAPOLIS, MINNESOTA.

AXLE AND HUB ATTACHING DEVICE.

SPECIFICATION forming part of Letters Patent No. 249,258, dated November 8, 1881.

Application filed August 30, 1881. (No model.)

To all whom it may concern:

Be it known that I, FRED RICE, of Minneapolis, in the county of Hennepin and State of Minnesota, have invented certain new and useful Improvements in Axles and Axle-Skeins; and I do hereby declare the following to be a full and exact description of the same, reference being had to the accompanying drawings, forming part of this specification, in which—

10 Figure 1 is a longitudinal sectional view of the invention; Fig. 2, an elevation of the same, and Fig. 3 a sectional view of the follower-nut.

Similar letters of reference in the several figures indicate the same parts.

15 My invention has for its object to provide an improved axle and skein constructed so as to exclude all sand and dirt from the bearing, and prevent liability of oil accumulating at the outer end in position to be transferred to the 20 clothing of a passer-by, and which will enable the wheel to run easily and noiselessly.

Referring to the drawings, A represents the hub of a carriage-wheel of ordinary construction, fitted within which so as to rotate there- 25 with is a skein, E, the outer or smaller end of which is closed, while its inner end is provided with an internally screw-threaded enlargement, as shown. This skein is constructed to receive the end of an axle, B, and is adapted to rotate 30 freely thereon, being prevented from longitudinal movement in one direction by an adjustable collar, D, and in the opposite direction by a follower-nut, C, as shown in Fig. 1.

Between the end of the axle and the end of 35 the skein is interposed a washer or packing, F.

In applying the wheel to the axle the collar D is adjusted so that when the skein is slipped onto the axle the end of the latter will slightly compress the washer F before the shoulder at the inner end of the skein comes in contact 40 with the collar. The follower-nut C is then screwed into the screw-threaded enlargement of the skein and up against the collar, thereby drawing the parts together and forming a close joint, which prevents the entrance of dust, dirt, 45 or any other foreign matter to the bearing. The outer end of the skein being closed, of course the lubricating-oil has no opportunity of collecting there, as in the ordinary skein, and the clothing of persons coming in contact 50 with the same is not liable to be soiled. As the parts wear, the position of the adjustable collar can be changed to compensate therefor.

Having thus described my invention, I claim as new—

55 The combination, with the axle screw-threaded, as described, of the collar screwed onto the axle, the skein having the closed outer end and the enlarged internally screw-threaded inner end, and the follower-nut screwed into the 60 skein and bearing up against the collar, the parts being so arranged that the follower-nut can be unscrewed and slid along the axle and the skein then slipped off, substantially as de- scribed.

FRED RICE.
